UNITED STATES PATENT OFFICE.

ELBERT W. FORD, OF JAMESTOWN, NEW YORK.

GAME APPARATUS.

1,425,376.

Specification of Letters Patent. Patented Aug. 8, 1922.

Application filed April 2, 1921. Serial No. 457,842.

To all whom it may concern:

Be it known that I, ELBERT W. FORD, a citizen of the United States, residing at the city of Jamestown, in the county of Chautauqua and State of New York, have invented 5 certain new and useful Improvements in Game Apparatus, of which the following, taken in connection with the accompanying drawings, is a specification.

10 The invention relates to improvements in game apparatus; and the object of the improvement is, first, to provide a toy of the class described having a target holder comprising a foldable upright frame with adjustable swinging trapeze thereon and a base plate for said upright frame and folding braces on said upright frame engaging said base plate; and second, to provide a slidably mounted toy catapult having means for 15 throwing a small projectile such as a toy doll or ball at said swinging trapeze or a target having an opening therethrough for said projectile; and third, to provide said toy doll with hooked arms which engage 20 over said trapeze to swing said doll between said uprights when the shooter is sufficiently skilled to drop the arms of the doll onto the cross piece of said trapeze; and the invention consists in the novel features and 25 combinations hereinafter set forth and 30 claimed.

In the drawings, Figure 1 is a perspective view of the game apparatus with the toy doll in position on the toy catapult for shooting, 35 a second doll being shown hanging from the trapeze as when thrown by the catapult to that position. Fig. 2 is a lengthwise sectional view of the toy catapult or shooter with a ball in position for throwing, the 40 position of the parts in the act of throwing being shown in dotted outline with means for abruptly stopping the shooter plate. Fig. 3 shows a plan view of the support and bracket in the folded position ready for 45 shipment or placing in a box for storage; and Fig. 4 is an end view of the same. Fig. 5 is an elevation of the front of the upright with the ring target depending before the same. Fig. 6 is a side elevation of the 50 upright and support in the process of folding. Fig. 7 is a plan view of the rear side of the target showing the supporting wires thereon. Fig. 8 is an edgewise elevation of the target and upright as shown in Fig. 5, the 55 supporting and back stop plates being broken away.

Like characters of reference refer to corresponding parts in the several views.

The entire apparatus is preferably made of sheet metal with the exception of the projectiles. The numeral 10 designates the supporting or base plate which is preferably struck up from sheet metal in the channel-shaped form to provide tracks by the upturned flanged edges 11. The upright inverted U-shaped frame 12 is pivotally attached to the flanges 11 near one end of the plates 10 and has the braces 13 pivotally attached near the lower end of each leg to removably engage in holes 14 in the flanges 11, which holes are the spaced distance required to hold the upright frame 12 in vertical position as to plate 10.

The U-shaped strap piece 15 is also pivotally attached near the lower end of the upright 12 at each side and extends to the rear having the incline portion 16 to support a back stop plate 17 at the incline of the portion 16 of the strap piece 15. A double hooked brace 18 may be provided to engage 80 over the upper end of the back stop plate 17 and over the top cross piece 19 of the upright 12 to hold the parts rigidly.

The upright 12 is also provided with a series of spaced holes 20 in the upper portion of each downward leg to receive therein the out-turned ends 22 of the spring wire trapeze 21 which swings between the two legs of the upright 12. Said trapeze may be made in the simple form shown in Fig. 1, or with additional swing wire 23 which is attachable to the rear side of a target ring 24 by means of suitable brackets and to the top cross bar of the frame 12 and hangs so that the projectiles may be shot through the hole 25 in the ring target 24, the target 24 being turned up on top, as shown in Fig. 1, when not in use.

The catapult consists of the inverted channel-shaped plate 26 which slidably fits over the flange tracks 11 of the plate 10 and has the convex shooter plate 27 pivotally attached to a sheet metal V-shaped raised support 28 at its apex 29, the raised support 28 being attached to the plate 26 at the out-turned lower ends 30 by riveting or welding. A rivet 31 is preferably provided on the side toward the end of the plate 26 which extends below said plate 26 a sufficient distance to receive thereon the elastic rubber strip 32, which strip has a series of holes 33 through the same to be received over the

struck-up hook 34 so that when the preferably convex or trough-shaped shooter plate 27 is thus attached, it can be balanced downward at the other and thereby giving 5 strong tension to the same through the elastic strip 32 when caught beneath the spring catch 35 at its end. A lug 36 is preferably struck up from the spring shooter plate 27 a spaced distance from the end thereof near 10 the spring catch 35, which serves as a holding means for the ball 37, a doll 38 or other projectile.

The doll projectile 38 is provided with the raised hooked arms 39, and is preferably of 15 a light celluloid type, though wood forms a good substitute. The feet of the doll may be weighted to cause said doll to swing downward easily in shooting the same onto the trapeze 21. The arms 39 are preferably 20 made of wire, which may be in a single piece and extend through the shoulders of the doll-shaped projectile, or of celluloid with hooks on the hands.

It is now apparent that the catapult plate 26 may be placed at the desired distance from the upright 12 and trapeze 21 and target 24 and that the doll 38, ball 37 or other projectile may be placed in the trough-shaped spring shooter plate 27, the end of 30 said shooter plate set beneath the spring catch 35 thereby setting the catapult in form for shooting said projectile so that by the quick withdrawal of the spring catch plate 35, the end of the spring shooter plate 27 is released, thereby throwing the projectile 35 as shown in dotted outline in Fig. 2 directly at the target or trapeze. The shooter plate 27 is abruptly stopped by the side of the V-shaped raised support 28, thereby giving 40 a short snappy throw to the projectile.

In the case of the hooked-arm doll 38 39, the skill is shown in so shooting said doll as to hook the arms 39 over the cross bar of the trapeze 21, and in the case of the ball, 45 to shoot the same through the opening 25 in the target 24. The doll 38 may be also shot through said opening 25 in the target 24, thus making a more difficult shot than without said target. The target 24 is preferably 50 made removable by swinging over on top of the frame so that the trapeze 21 may be used with or without the same. The back stop plate 27 is usually struck by the projectile which slides down the same onto the plate 55 11 ready to be replaced on the spring shooter plate 27.

The parts 10, 12, 17 and 18 are made foldable by the withdrawal of the hooked braces 13 from the openings 14, thereby permitting 60 the upright 12 to be folded into the channel plate 10 and the back stop plate 17 to be folded over the same. The target 24 and brace 18 being removable are placed between the back stop plate 17 and supporting plate 65 10, 11.

A pair of braces 40 may also be pivotally attached to the uprights 12 a spaced distance above the strap piece 15 to engage behind and support the back stop plate 17, said braces 40 being foldable within the upright 70 12, making a compact folded device as shown in Figs. 3 and 4. The catapult plate 26 sets over the channel plate 10 and other parts when in the folded position, thereby giving the entire apparatus a compact form 75 for shipment or storage.

What is claimed is:

1. A game apparatus comprising a base plate having parallel tracks thereon, an inverted U-shaped frame pivotally attached 80 to said parallel tracks near one end of said base plate, detachable braces between said tracks and said frame to support the same in an upright position, said frame having a lengthwise series of holes in each leg thereof, a wire trapeze sprung into said holes to adjustably and swingingly support the same in said frame, a spring shooter slidably mounted on said tracks on said base plate to adjust said shooter as to distance from said trapeze, and a hook projectile to be thrown by said spring shooter endeavoring to hang the same on said trapeze. 85

2. In a game apparatus, a base plate having its sides turned upwardly to form flanges, a frame of less length than that of the base plate slidably seated on the upper edges of the flanges and having its sides turned downwardly to slidably engage over the outer faces of the flanges, a projectile 90 shooter on the frame, an inverted U-shaped target carrying frame having its free ends pivoted to the flanges, and means to hold the target frame vertical and against pivotal movement. 95

3. In a game apparatus, a base plate having its sides turned upwardly to form flanges, a frame of less length than that of the base plate slidable on the base plate and having its sides turned downwardly and engaged with the flanges, a projectile shooter on the frame, an inverted U-shaped target carrying frame having its free ends pivoted to the flanges, and means to hold the target frame vertical and against pivotal movement. 110

4. In a game apparatus, a base, an inverted U-shaped target frame pivoted to the base so as to fold thereagainst, means between the frame and base to hold the frame vertical and against pivotal movement, a back stop plate pivoted to the base so as to fold against the target frame plate, a latch pivoted to the top of the frame and engageable with the top of the back stop plate to hold the latter at an incline and to the rear of the frame, and a shooter on the base. 120

5. In a game apparatus, a base, a shooter thereon, an inverted U-shaped target frame 125 130

pivoted to the base so as to fold thereagainst, means between the frame and base to hold the frame vertical and against pivotal movement, a back stop plate pivoted to the base 5 so as to fold against the target frame plate, and a horizontal U-shaped member having its ends attached to the legs of the frame and receiving the back stop plate therebetween and having its body engaged with the rear 10 of the back stop plate to hold the latter at an incline and to the rear of the frame.

6. In a game apparatus, a base, a shooter thereon, an inverted U-shaped target frame pivoted to the base so as to fold thereagainst, 15 means between the frame and base to hold the frame vertical and against pivotal movement, a back stop plate pivoted to the base so as to fold against the target-frame plate, and a pair of L-shaped members pivoted to 20 the respective legs of the frame and having their angular ends engageable with the rear of the back stop plate to hold the latter at an incline and to the rear of the frame.

7. In a game apparatus, a base, an inverted U-shaped target frame pivoted to the base, means between the frame and base to hold the frame vertical and against pivotal movement, a back stop plate pivoted to the base plate, a latch pivoted to the top of 25 the frame and engageable with the back 30

stop plate to hold the latter at an incline and to the rear of the frame, and a target pivoted to the top of the frame and movable to lie on top of the latch, so as to be held thereby.

8. In a game apparatus, a base, a frame thereon having spaced vertical sides each formed with spaced perforations and a wire trapeze of U-shape having its free ends turned at right angles and engaged with 40 certain of the perforations in the respective sides of the frame.

9. In a game apparatus, a base, a target frame thereon, and a projectile shooter including a frame, an inverted V-member on 45 the shooter frame having its ends turned outwardly and secured thereto, a shooter tensioned member pivoted to said V-member, and a latch for the shooter member consisting of a metal strip having one end 50 turned outwardly and secured to the shooter frame and having its opposite end formed with a catch to engage the shooter member.

In testimony whereof I have affixed my signature in the presence of two witnesses. 55

ELBERT W. FORD.
